UNITED STATES PATENT OFFICE.

WILLIAM W. JOHNSTON AND WILLIAM THOS. WATTS, OF DONIPHAN,
MISSOURI.

TYPE-WRITER CABINET.

No. 810,416.

Specification of Letters Patent.

Patented Jan. 23, 1906.

Application filed April 22, 1905. Serial No. 256,966.

To all whom it may concern:

Be it known that we, WILLIAM W. JOHNSTON and WILLIAM THOS. WATTS, citizens of the United States of America, residing at Doniphany, in the county of Ripley and State of Missouri, have invented new and useful Improvements in Type-Writer Cabinets, of which the following is a specification.

This invention relates to desks, and particularly to means for supporting a type-writer thereon, and has for its objects to produce a comparatively simple inexpensive device of this character whereby the type-writer may when not in use be readily entered into its compartment within the desk, one in which the type-writer-carrying leaf or table may be moved to operative position, and one wherein the door of the compartment performs the further function of a retaining member for supporting the leaf in active position.

With these and other objects in view the invention comprises the novel features of construction and combination of parts more fully hereinafter described.

25 In the accompanying drawings, Figure 1 is a perspective view of a desk embodying the invention. Fig. 2 is a vertical section taken centrally through the type-writer-receiving compartment of the desk. Fig. 3 is a front elevation of said compartment, showing the door in open position. Fig. 4 is a section taken on the line 4-4 of Figs. 2 and 3. Fig. 5 is a detail view showing the pivoted section of the door in folded position.

35 Referring to the drawings, 1 designates a desk which, except as hereinafter explained, is of the usual or any appropriate construction and material, it being understood in this connection that while the desk is illustrated 40 herein as being of the cabinet or flat-top type it may be of the ordinary roller-top construction.

In accordance with this invention the desk is provided with a compartment 2, having at 45 its rear end vertical weight-guides 3, designed to receive weights 4, suspended from flexible elements or cords 5, which in turn travel over guide-pulleys 6 and are engaged at one end with a type-writer-carrying leaf or table 7, 50 said leaf being pivoted at its normally inner or upper end by means of hinges 8 to the top of the desk and within the compartment 2. It is to be observed in this connection that the leaf or table normally hangs in a substan-

tially vertical position wholly within the compartment and that under these conditions the weights 4 are, through the medium of the cords 5, drawn to a position at the upper ends of the guides 3, it being understood that the weights are sufficiently heavy to counterbalance the leaf when a type-writing machine is in position thereon for a purpose which will presently appear.

55 The compartment 2 is normally closed by means of a door 9, having at its upper end a 60 movable member or section 10, pivoted to the door by means of a hinge 11, the section 10 being of a form to fit within a recess 12, formed in an apron 13 at the upper outer end of the compartment, it being observed in this 65 connection that the leaf 7 is of a cross-sectional form to likewise fit within the recess.

Pivoted to the leaf 7 at a point adjacent its free end and by means of a bolt or pintle 14 is a turn-table 15, on which the type-writing 70 machine rests and to which it is attached in any appropriate manner, said turn-table being normally fixed against movement by a locking member or pin 16, entered into registering 75 openings in the turn-table and leaf.

80 In practice the leaf having the type-writing machine attached thereto normally hangs suspended within the compartment 2, as heretofore explained and as illustrated in Fig. 2, the door 9 being under these conditions closed for 85 completely housing the machine within the compartment. When it is desired to use the type-writer, the door 9 is opened and the section 10 folded downward, as illustrated in Fig. 5. The leaf 7 is next swung outward to a 90 horizontal position, as seen in Fig. 1, whereby it will, as before stated, fit within the recess 12, thus permitting the door to be closed, the door serving under these conditions to sustain the leaf in its active or horizontal position. 95 It may be mentioned in this connection that owing to the weights 4 counterbalancing the weight of the leaf 7 and machine carried thereby the leaf may be moved to active position with but slight exertion on the part of the operator.

100 From the foregoing it is apparent there is produced a simple inexpensive device in which the machine will when not in use be fully protected from dust and like impurities and one 105 wherein the leaf may be readily moved to and fixed in position for supporting the type-writer when in use, it being understood that

minor changes in the details herein set forth may be resorted to without departing from the spirit of the invention.

Having thus described our invention, what we claim is

- 5 1. A desk having a compartment and a recess provided at the upper end thereof, a leaf pivoted to swing to a position within the compartment, said leaf being adapted to move to a horizontal position and seat within the recess, and a door for the compartment having a movable section designed to normally close the recess.
- 10 2. A desk having a compartment and a re-

cess provided at the upper end thereof, a leaf pivoted within the compartment to swing in a vertical plane, said leaf being of a form in cross-section to fit within the recess, and a door for the compartment having a movable section designed to fit and normally close the recess.

In testimony whereof we affix our signatures in presence of two witnesses,

WILLIAM W. JOHNSTON.
WM. THOS. WATTS.
